LOCKING DEVICE

Rafael Rivas, New York, N. Y., assignor of one-third to Sidney Weinryb and one-third to Samuel Bluestein, both of New York, N. Y.

Application October 30, 1936, Serial No. 108,340

9 Claims. (Cl. 232—42)

This invention relates to locking devices adapted primarily although not exclusively for use with milk bottles, the purpose thereof being to enable articles particularly with flanged, beaded or enlarged upper portions to be readily inserted in place and retained or locked therein against abstraction by unauthorized persons. And when employed for milk bottles, it is the further purpose of this invention to prevent access 10 to or exposure of the mouths of the bottles retained therein so as to keep them in proper sanitary condition.

Milk bottle locks of this general class have been known or used before, particularly in cooperable relation with a door and frame or jamb thereof, but such devices have usually employed spring or resilient members, have often been intricate in structure and hence expensive to fabricate, and frequently insecure as a locking medium. It is one of the objects of my invention to eliminate, in 15 a device of this category, the aforesaid shortcomings, and enable an inexpensive structure of simple and rigid design to efficiently accomplish its operative purpose, and without the use of any 20 springs or other resilient members.

It is also within the contemplation of this invention to provide multiple locking means as a positive assurance against the removal of the articles operatively positioned within the device.

Still another object is to enable the portable portion of the device constituting my invention to be readily secured in place and conveniently detached therefrom, and also to provide inaccessible fastening means for the support for said 35 portable portion when it is in its normal operative position.

And it is within the further contemplation of this invention to permit the portable portion thereof to be conveniently carried without danger 40 of causing the articles therein to fall out, and to enable such articles to be quickly and easily removed by a simple manipulation.

And a further object of my invention is to enable a structure made in accordance with this invention to operatively and conveniently hold 45 therein a relatively large number of articles.

Other objects, features and advantages will appear from the drawing, and the description hereinafter given.

50 Referring to the drawing,

Figure 1 is a front view of my invention shown holding two milk bottles and operatively attached to a closed door.

Figure 2 is a vertical longitudinal section of one 55 form of my invention, illustrating one milk bottle in place, and another being inserted.

Figure 3 is a view similar to Figure 2, both bottles being shown in place, a tongue and an elbow of extended lengths being shown in dot-dash lines as alternative arrangements.

Figure 4 is a transverse section of Figure 2 taken along line 4—4.

Figure 5 is a bottom view of Figure 2, with the bottles removed, and illustrating the manner of attachment of the portable portion to the door, 5 and

Figure 6 is a modified form of my invention adapted for use independent of a door, and also illustrating an extended body portion for accommodating three milk bottles.

In the drawing, and in the preferred embodiment of my invention, the hollow and preferably rectangular-shaped retaining chamber or receptacle 7 has the inlet end portion 8 thereof closed, the outlet end 9 being open. The lateral sides 10 and 11 of the said receptacle have inturned flanges 12 and 13 forming runways for slidably accommodating the beaded or enlarged upper portions such as 14 and 15 of the milk bottles 16 and 17. The said runways 12 and 13 extend rearwardly along a portion of the base of the receptacle 7, leaving a sufficient aperture 23 at the forward part of the device to permit the insertion of the upper portion of the bottle with the said beads thereon. The space between the said runways is 25 sufficiently wide to permit the necks of the bottles to extend therethrough.

Rotatably supported near the roof of the receptacle 7, preferably by the walls 10 and 11 thereof, are the gate 18, the flap or plate 19 and the angulated member or lever 20 comprising the rearwardly extending tongue 21 and the forwardly extending locking elbow 22.

In the operation of this device, an article such as the bottle 16 is inserted through the aperture 35 23, thereby raising the gate 18 and the flap 19 to the position shown in Figure 2. The bottle is then slidably moved along the runways 12 and 13 to the right until it is in the position shown in Figure 3. At this point, the top of the bottle 40 actuates the tongue 21 upwardly causing the locking elbow 22 to be lowered to the position shown.

The device is now in its locking position, the gate 18 having swung downwardly either under its own weight aided by the pressure exerted thereupon by the flap 19, or by the action of elbow 22 thereupon. The said gate 18 completely prevents access to the interior of the receptacle 7 supporting the bottle, due to the fact that the said gate 45 cannot rotate in a clockwise direction because it rests upon the flanges or runways 12 and 13 and is prevented from moving therewith. Neither can the gate move in a counterclockwise direction

inasmuch as the locking elbow 22, forced downwardly by the action of the bottle 16 upon the tongue 21, is adjacent the flap 19 and holds it, and consequently the gate, against any counterclockwise movement. If the locking elbow is 50 made with a sharper angulation, as is indicated in dot-dash lines by the numeral 22a, it will be 55

60 made with a sharper angulation, as is indicated in dot-dash lines by the numeral 22a, it will be 60

engageable directly with the gate, and have the same effect. In either event, the elbow is interposed in the path of the gate to hold it against opening. It is thus apparent that by the simple 5 operation of inserting the bottle 16 past the said gate 18 into the position shown in Figure 2, the device has accomplished its locking function. The action herein described characterizes an important feature of my invention; and its practical application in cooperation with a door will 10 now be described.

Secured to the door 24 is the plate or support 25 containing the hollow ears 26 and 27. The receptacle 7 contains the bars 28 and 29 in spaced 15 parallel relation to the wall 11 and adapted to be operatively received by the said ears 26 and 27. In attaching the receptacle or portable portion of this device in place, the door is opened, and the said bars 28 and 29 slipped into the ears, and 20 thereafter the door is closed. The parts are so positioned that the space 30 between the open end 9 of the device and the frame or jamb 31 of the door is insufficient to permit a bottle to pass therethrough. The bottles are inserted, as aforesaid, through the opening 23 and slid to the right until they are operatively in position. They cannot be removed through the said aperture 23 due to the locking action above described, the gate 18 being held closed. Neither can they be removed from the right or open-end of the device 25 due to the proximity of this end from the jamb 30 as above indicated.

To remove the bottles from the receptacle 7, the door is opened, and the portable portion removed 35 from its operative engagement with the plate 25, the handle 32 serving to facilitate such manipulation. Once the receptacle is out of its locked position, the bottles can be removed through the opening 9 as will be more specifically set forth 40 hereinafter.

It will be noted that the plate 25 is secured to the door by the screws 33, 34, 35 and 36. It is apparent that when the receptacle 7 is in its operative position on the door, the said screws 45 are not accessible,—thereby making it extremely difficult to remove the entire device from its fastening on the door.

Although the device is shown attached to a door, it can be equally effective if secured to the 50 jamb or a wall at right angles to the plane of the door, and in such proximity to the door as to render the withdrawal of a bottle impossible unless the door is opened.

In the description hereinabove given of the 55 operation of the device, the action with reference to a single bottle was described. The receptacle 7, however, is adapted to accommodate, in the form shown in Figures 1 to 5, two bottles, the bottle 17 having been inserted into position in 60 a manner similar to that applied to bottle 16.

In Figure 6 is shown an arrangement where the receptacle 37 is of extended length so as to operatively accommodate three bottles therein. It is of course apparent that the number of bottles that 65 could be accommodated is limited only by the length of the receptacle. In the structure of Figure 6, one of the bottles, such as 38 is in operative engagement with the tongue 39, in the manner hereinabove described, although it is obvious that 70 any of the other bottles can be in similar engagement with the said tongue provided the latter is made of the proper length.

It will be noted in referring to Figure 2 that 75 prior to the insertion of bottle 16, bottle 17 has already been put into place. This bottle cannot

be removed through the opening 9 when the receptacle is in its operative position on the door; neither can it be removed past the tongue 21 which is now in its lowered position to which it has fallen under its own weight, thereby serving 5 as a closure. Should the said tongue be elevated by a finger or tool inserted through the aperture 23 in an attempt to remove the bottle 17, the said upward movement of the tongue will cause a downward movement of the locking elbow 22 to 10 force the gate 18 into its closed position. It is hence apparent that this device constitutes a double assurance against pilferage, one by the closure effected by the tongue 21 in the instance described, and the other by the closure effected 15 by gate 18 under the action of elbow 22. It will be noted that the elbow 22 serves the additional function of limiting the downward swing of the tongue 21, thereby acting in a dual locking capacity. 20

It is of course understood that the tongue 21 can be made of various lengths, and can extend to the bottle 17 if elongated to the length of tongue 40 shown in dot-dash lines in Figure 3.

It will be observed, particularly by referring to Figures 2, 3 and 5, that the runways 12 and 13 are upwardly bent at the rear thereof, that is near the open end 9. When the receptacle 7, constituting the portable portion of the device, is removed from the door in the manner aforesaid, 30 and carried by gripping the handle 32, the bottles cannot slip out through the open end 9, due to the obstruction afforded by said upwardly turned ends 44 and 45. When it is desired to remove the bottles, they are either manually elevated until the beads clear such upturned portions 44 and 45 and then removed, or the entire device with the bottles depending therefrom is placed upon a table whereupon the receptacle 7 will drop down upon the tops of the bottles. In this position the beads of the bottles will be above the level of the said upturned portions 44 and 45, and the receptacle 7 can then be slid outwardly to free the bottles. 35

It is within the contemplation of this invention not to limit this device for use in conjunction only with a door, inasmuch as it can be employed as an independent device. By referring to Figure 6 it will be seen that the rear portion of the receptacle contains a hinged door 41 adapted to 50 be locked by the locking means 42. In the operation of this form of my invention, the door 41 is normally locked, and the bottles inserted through the aperture 43. If it is desired to remove the bottles, in this form of my invention, 55 the door 41 is unlocked and the bottles slipped out therethrough.

Although the device constituting my invention is shown employed in conjunction with milk 60 bottles, it is obvious that it is equally applicable for use with other articles, such as those containing enlarged upper portions, flanges or beads. It is likewise adaptable for use with other articles that can be contained wholly within the device, 65 and not extending through the base thereof. 70

It is of course understood that the various embodiments above described and shown in the drawing are illustrative of my invention and not employed by way of limitation, inasmuch as numerous changes and modifications may be made within the scope of the appended claims without departing from the spirit of this invention. 75

What I claim is:

1. In a locking device, a hollow receptacle for 75

supporting an article therein and having an inlet and outlet opening therefor, a gate adjacent said inlet opening and entirely confined within said receptacle, said gate being swingable inwardly towards its open position, a pivotally mounted lever comprising a tongue and an elbow angulated with respect thereto, the tongue being adapted to be operatively actuated by the engagement therewith of said article when positioned within the 10 receptacle, thereby causing a movement of the elbow to a position within the path of said gate, and means for obstructing said outlet opening.

2. In a locking device, a hollow receptacle for supporting an article therein and having an inlet 15 and outlet opening therefor, a gate adjacent said inlet opening and entirely confined within said receptacle, said gate being swingable inwardly towards its open position, means in constant engagement with the gate urging it towards its 20 closed position, a pivotally mounted lever comprising a tongue and an elbow angulated with respect thereto, the tongue being adapted to be operatively actuated by the engagement therewith of said article when positioned within the 25 receptacle, thereby causing a movement of the elbow to a position adjacent said means and engageable therewith to hold the gate against swinging inwardly, and means for obstructing said outlet opening.

30 3. In a locking device, a hollow receptacle for supporting an article therein and having an inlet and outlet opening therefor, a pivotally mounted gate adjacent said inlet opening and entirely confined within said receptacle, said gate being swingable inwardly towards its open position, a pivotally mounted flap constantly bearing against said gate to urge it towards its closed position, a movable member within the receptacle operatively engageable with the flap, said member 35 being adapted to be operatively actuated by the engagement therewith of said article when positioned within the receptacle, and means for obstructing said outlet opening.

4. In a locking device, a hollow receptacle for 45 supporting an article therein and having an inlet and outlet opening therefor, a pivotally mounted gate adjacent said inlet opening, a pivotally mounted flap bearing against said gate to urge it towards its closed position, a pivotally mounted 50 lever adapted to be operatively actuated by the engagement therewith of said article when positioned within the receptacle, thereby causing one extremity of the lever to move to a position where it will be engageable with the flap to hold the 55 gate against opening, and means for obstructing said outlet opening.

5. In a locking device, a hollow receptacle for 60 supporting an article therein and having an inlet and outlet opening therefor, a gate pivotally mounted from the upper portion of the receptacle and extending obliquely downwardly and rearwardly and resting upon the base of the receptacle adjacent said inlet opening, a pivotally mounted flap to the rear of the gate and bearing 65 against the gate to urge it towards its closed position, a pivotally mounted lever comprising a tongue and an elbow angulated with respect thereto, the tongue being adapted to be operatively actuated by the engagement therewith of 70 said article when positioned within the receptacle, thereby causing a movement of the elbow to a position where it will be engageable with the flap

to hold the gate against opening, and means for obstructing said outlet opening.

6. In a locking device, a hollow receptacle for supporting an article therein and having an inlet and outlet opening therefor, a pivotally mounted gate adjacent said inlet opening, a pivotally mounted flap bearing against said gate to urge it towards its closed position, a pivotally mounted lever one end of which is adapted to be raised by the engagement therewith of said article when positioned within the receptacle, thereby causing the other end to be lowered to a position where it will be engageable with the gate to hold it against opening, and means for obstructing said outlet opening.

15 7. In a locking device, a hollow receptacle for supporting an article therein and having an inlet and outlet opening therefor, a gate adjacent said inlet opening, a pivotally mounted lever comprising a tongue and an elbow angulated with 20 respect thereto, the tongue being adapted to be operatively actuated by the engagement therewith of said article when positioned within the receptacle, thereby causing a movement of the elbow to a position within the path of said gate, 25 the said lever being pivotally mounted near the upper portion of the receptacle in such manner that in its normal position the elbow thereof is adjacent the roof of the receptacle and the tongue extends downwardly to form a closure for the 30 receptacle; and means for obstructing said outlet opening.

8. In a holder for milk bottles or the like, a receptacle open along the base thereof and containing a bottom inlet at one end of the receptacle 35 and an outlet at the opposite end thereof, two runways flanking the opening in said base and extending rearwardly from said inlet opening, the runways being adapted to slidably accommodate the beaded tops of the bottles, a pivotally mounted gate adjacent said inlet, a pivotally mounted flap bearing against said gate to urge it towards its closed position, a movable member 40 within the receptacle and adapted to be raised by the engagement therewith of the top of an 45 underlying bottle, thereby causing a movement of said member to a position where it will be engageable with the flap to hold the gate against opening, and means for obstructing the said outlet.

50 9. In a holder for milk bottles or the like, a receptacle open along the base thereof and containing a bottom inlet at one end of the receptacle and an outlet at the opposite end thereof, two runways flanking the opening in said base 55 and extending rearwardly from said inlet opening to terminate in upturned ends near said outlet, the runways being adapted to slidably accommodate the beaded tops of the bottles, a gate adjacent said inlet and entirely confined 60 within said receptacle, said gate being swingable inwardly towards its open position, a movable member within the receptacle and adapted to be actuated by the engagement therewith of the top of an underlying bottle, means operatively 65 associated with said member and gate for holding the gate against being swung inwardly, said means being adapted to be operatively actuated by said member when the latter is actuated by said bottle, and means for obstructing said outlet. 70
